United States Patent Office

Des. 175,768
Patented Oct. 11, 1955

175,768

LUGGAGE CASE

Emmett H. Heitler, Denver, Colo., assignor to Shwayder Bros., Inc., Denver, Colo., a corporation of Colorado

Application January 27, 1955, Serial No. 34,264

Term of patent 14 years

(Cl. D87—5)

Fig. 1

Fig. 2

Fig. 3

Fig. 5

Fig. 4

Fig. 1 is a side elevation of a luggage case embodying my new design;

Fig. 2 is a perspective view of the luggage case of Fig. 1 on a reduced scale;

Fig. 3 is a top plan view of the luggage case, on the scale of Fig. 2;

Fig. 4 is a side elevation of the luggage case on the scale of Fig. 2; and

Fig. 5 is a perspective view of the luggage case, with the sections thereof in separated position.

The parts in the interior of each section of the luggage case are shown in dotted lines, the dominant features of my new design being shown in full lines.

I claim:

The ornamental design for a luggage case, as shown and described.
